UNITED STATES PATENT OFFICE.

PATRICK J. LUCEY, OF SOUTH BEND, INDIANA, ASSIGNOR TO LUCEY SLICING MACHINE CO., OF SOUTH BEND, INDIANA.

DEFLECTING PLATE FOR SLICING MACHINES.

Application filed January 24, 1925. Serial No. 4,520.

The invention relates to meat slicing machines, and has for its object to provide a deflecting plate for the slicing machine which may be readily removed and replaced without the use of tools or manipulation of any nuts, screws or the like, whereby the easy and quick removal of the deflecting plate will encourage the frequent cleaning thereof, as all surfaces of the plate 5 may be easily and quickly cleaned when removed. Plates of this character are at present secured to slicing machines with nuts and bolts, with the result that many operators of slicing machines will not take the 10 time and trouble to remove the deflecting plate for freeing the same of the accumulations of dust, dirt and small meat scraps, consequently the rear sides of these plates, as well as the inner sides of the wings there- 15 of are unsanitary, and it is practically im- possible to clean these surfaces without removing the plate, especially the side of the wing adjacent the cutting disc, which on ac- 20 count of its close proximity to the cutting disc can not be properly cleaned without removal of the plate, consequently it is gen- 25 erally in an unsanitary condition.

A further object is to provide the deflecting plate with shafts having shoulders, 30 which shafts have their outer ends rigidly attached to the plate and spring actuated latching means cooperating with the shoul- ders of the shafts for holding the deflecting plate in position and means in connection 35 with the latching means whereby all of the latching devices may be simultaneously moved to inoperative position for allowing removal of the deflecting plate.

A further object is to provide sleeves 40 against which the inner ends of the shaft en- gage when the deflecting plate is placed in position and coiled springs surrounding said sleeves and compressed when the deflecting plate is forced into position, said coiled 45 springs also form means for forcing outwardly on the shafts when the plate is being removed thereby allowing the plate to be easily and quickly removed, and assisting in the removal operation. Also to pro- 50 vide means for limiting the outward move- ment of the sleeves in registration with ap- 55 ertures through which enlargements carried by the shafts are received.

A further object is to dispose the latching 60 means within a U-shaped channel secured

to a bracket and to mount the latching de- 60 vices on a rotatable shaft in said channel, and to provide spring means cooperating with the latching devices for forcing the same to operative position in engagement with the shoulders of the shaft, said shoul- 65 ders of the shaft being constructed whereby when they are forced to position when re- placing the deflecting plate the latching de- 70 vices will be forced outwardly against the action of the springs until the shoulders are received behind the hooked ends of the latching devices.

With the above and other objects in view 70 the invention resides in the combination and arrangement of parts as hereinafter set forth, shown in the drawing, described and claimed, it being understood that changes in the precise embodiment of the in- 75 vention may be made within the scope of what is claimed without departing from the spirit of the invention.

In the drawing:—

Figure 1 is a front elevation of the slicing machine.

Figure 2 is a perspective view of a portion 80 of the slicing machine, showing the deflector plate.

Figure 3 is a vertical longitudinal sec- 85 tional view taken on line 3—3 of Figure 2.

Figure 4 is a view similar to Figure 3, showing the deflector plate partially re- 90 moved.

Figure 5 is a horizontal sectional view taken on line 5—5 of Figure 3.

Referring to the drawing, the numeral 1 90 designates the frame of a meat slicing ma- chine, and 2 a longitudinally movable car- riage, on which meat is placed, and which carriage reciprocates for moving the meat 95 intermittently against the rotatable cutting disc 3. Disposed adjacent the cutting disc 3 and extending upwardly from the frame 1 is a bracket 4, and all of which structure is of a conventional form. It has been found 100 where deflector plates are used, they are always secured in a manner whereby it re- quires tools of various kinds to remove the same for cleaning purposes, for instance they are secured by screws or bolts. It has also 105 been found that where deflector plates are secured, the operator of the machine will not take the trouble to remove the screws for removing the plate and cleaning the same, and to obviate the above difficulty the present 110

invention is primarily designed, as it is essential to keep the machine in a sanitary condition, and this cannot be done unless the plate 5 is removed, which plate is provided with the wing 6 adjacent the cutting disc 3, and dirt and particles of meat accumulate on the back of the plate 5 and on the surface of the wing adjacent the disc 3, consequently it is essential to remove the plate to reach these parts. Secured to the deflector plate 5 by means of riveting at 7 are rearwardly extending shafts 8, which shafts are provided with frusto conically shaped shoulders 9, over which the noses 10 of the latching members 11 extend for holding the plate 5 in close engagement with the wall 12 of the casing 13 which is secured by means of screws 14 to the extension 15 carried by the bracket 4. Latching members 11 are mounted on an upwardly inclined shaft 16, the ends of which are rotatably mounted in bearings 17 of the casing 13, therefore it will be seen that when the operator grasps the knob 18, carried by the upper end of the shaft 16, and rotates the same, the latching members 12 may be moved outwardly to a position where the shaft 8 and the frusto conically shaped shoulders 7 carried thereby may move outwardly through the apertures 19 in the wall 12 of the casing 13, consequently the deflector plate 5, which carries the shafts 8, may be easily unlatched and removed. The lower end of the shaft 16 is provided with an arm 20, to which is connected at 21 a coiled spring 22, and which coiled spring is anchored at 23 to the wall 12 of the casing 13, therefore it will be seen that when the shaft 15 is rotated for moving the latching members 11 to inoperative position, the spring 22 will be stretched, and when the operating knob 18 is released, the spring 22 will move the latching members 11 to a position whereby, when the shafts are passed into the casing 13, the frusto conically shaped shoulders thereof will force the latching members 11 outwardly until they are released by the shoulders 9 passing beyond the noses 10 thereof, and at which time the deflecting plate will be in a position in engagement with the wall 12 of the casing 13, therefore it will be seen the deflecting plate may be easily removed and replaced without the use of tools of any character.

Disposed within apertures 24 in the bracket extension 15, and the reduced apertures 25 are slidable sleeves 26, the outer ends of which sleeves are provided with annular flanges 27, and interposed between the annular flanges 27 and the bottoms of the apertures 24 are coiled springs 28, and which coiled springs normally force the sleeves 26 outwardly. The outward movement of the sleeves 26 is limited by the plate 29 secured to the outer face of the bracket-extension 15. Shafts 8 are provided with cylindrical en-

largements 30, which when the shafts are forced inwardly pass through apertures 31 in the plate 29, and into engagement with the outer ends of the sleeves 26, therefore it will be seen that when the shafts 8 are forced inwardly the sleeves 26 are also forced inwardly and the coiled springs 24 compressed. When the latching members 11 are moved to inoperative position, the springs 24 force the sleeves 26 outwardly while in engagement with the cylindrical enlargements 30 of the shafts 8, and consequently the plate 5 is forced outwardly thereby facilitating the removal of the deflector plate and the wing 6 carried thereby. The inner ends 8a of the shafts 8 preferably extend into the outer ends of the sleeves 26, thereby insuring an accurate seating of the enlargements 30 against the outer ends of the sleeves.

From the above it will be seen that a securing means for deflector plates of meat slicing machines is provided, whereby the deflector plate and its wing may be easily and quickly removed from the machine without the use of tools of any kind, and the deflector plate and wing may be thoroughly cleaned and easily and quickly replaced in position, thereby allowing the rear sides of the deflector plate and wing to be maintained in a sanitary condition at all times.

The invention having been set forth what is claimed as new and useful is:—

1. The combination with a plate and a support for said plate, of means for attaching said plate to said support, said means comprising shafts carried by the plate, shoulders carried by the shafts, a rotatable operating shaft, latching members carried by the operating shaft and cooperating with the shoulders when the plate is in position, spring means cooperating with the operating shaft for maintaining the latching members in engagement with the shoulders, and means carried by the operating shaft and adapted to be grasped by the operator for rotating the operating shaft.

2. The combination with a plate and a support, of means for attaching said plate to said support, said means comprising shafts carried by the plate, shoulders carried by said shafts, a rockable operating shaft, latching members carried by said operating shaft and cooperating with the shoulders, spring means cooperating with the operating shaft for maintaining the latching members in engagement with the shoulders and spring means cooperating with the inner ends of the plate shafts for forcing said last named shafts outwardly upon release of the latching members.

3. The combination with a plate and a support, of means for attaching said plate to said support, said means comprising shouldered shafts carried by the plate, latch-

ing members engaging over the shoulders of the shafts when in position, means for controlling said latching members, spring pressed sleeves engaging the inner ends of the plate shafts, said spring pressed sleeves forming means for forcing the plate shafts outwardly upon release of the latching members.

4. The combination with a plate and a support, of means for attaching said plate to said support, said means comprising a casing carried by the support, a rock shaft in said casing, latching members carried by said rock shaft, bolts carried by the plate and extending into the casing, shoulders carried by said bolts and with which the latching members cooperate, spring means for maintaining the latching members in operative positions, sleeves slidably mounted in chambers in axial relation to the bolts, coiled

springs surrounding the sleeves and forcing the same outwardly, means for limiting the outward movement of the sleeves, and enlargements carried by the plate shafts and adapted to engage the outer ends of the sleeves and compress the springs when the plate is forced to position on the support.

5. The combination with a plate and a support, of means for attaching said plate to said support, said means comprising shouldered shafts carried by the plate, latching members carried by the support, and spring means cooperating with the inner ends of the shouldered shafts whereby upon release of the latching means said shafts will be forced outwardly.

In testimony whereof I affix my signature.

PATRICK J. LUCEY.
